CARPET.

No. 17,666.

Patented Aug. 30, 1887.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 17,666, dated August 30, 1887.

Application filed July 6, 1887. Serial No. 243,555. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of several similar figures which are disposed irregularly upon the surface of the carpet.

Figure A is an assemblage of star-shaped 20 leaves or flowers ornamented with concentric bands or rings. Around the edges of the group

irregular coral shaped forms project, with a few small stems and leaves.

Figure B is composed of several star shaped leaves or flowers marked with concentric 25 rings or bands, with coral forms projecting at the sides, and between and around the coral-work pebbled or cellular ornamentation.

Figure C is circular in general outline, and is composed of three star-shaped leaves or flow- 30 ers marked with concentric rings or bands, with coral ornamentation at the sides.

What I claim as new, and desire to secure by Letters Patent, is—

1. The design for carpets, consisting of the 35 figure A, substantially as shown.

2. The design for carpets, consisting of the figures A, B, and C, substantially as shown.

JAS. L. FOLSOM.
